UNITED STATES PATENT OFFICE.

OZRO N. WISWELL, OF LOS ANGELES, CALIFORNIA, ASSIGNOR TO SWINGSPOUT MEASURE CO., A CORPORATION OF CALIFORNIA.

EMERGENCY UNIT MOUNTING.

Application filed January 5, 1922. Serial No. 527,208.

This invention relates to automobile emergency units, and relates particularly to a lockable means for securing the containers comprising the emergency unit upon the running board of an automobile.

It is an object of my invention to provide such a mounting which may be secured upon the running board of an automobile, which mounting will hold the containers rigidly and unremovably thereupon so that the containers will be inaccessible to all except authorized persons provided with keys to the locking means thereof.

It is a further object of my invention to provide a mounting that cannot be removed from the running board of an automobile while the containers are locked therein.

It is also an object of my invention to provide an emergency unit mounting which may be economically manufactured and which will present a workmanlike and agreeable appearance that will harmonize with the general structural design of automobiles.

Other objects and advantages will be made evident hereinafter.

Referring to the drawing, which is for illustrative purposes only,

Fig. 1 is an elevational view of an emergency unit with which my invention is employed mounted upon the running board of an automobile.

Fig. 2 is an end elevation taken as indicated by the arrow 2 in Fig. 1.

Fig. 3 is a fragmentary section taken upon a plane represented by the line 3—3 of Fig. 2.

Automobile emergency units are generally comprised of a number of containers, such as those shown at 11, 12 and 13, which containers may be respectively used to carry emergency supplies of water, oil and fuel. To secure these containers upon the running board 14 in such a manner that they may be held rigidly and without vibration thereupon, and also be inaccessible to unauthorized persons, I employ an arrangement of parts as shown in the drawing, comprising: a base 18 adapted to receive the lower ends of the containers 11, 12 and 13; a cover 19 to enclose the upper portion of the containers; and a locking mechanism 20 having arms 21 which engage the cover 19 by means of a hooked end 22 passing through eyes 23 formed in the cover 19.

Upon the vertical legs 30 of brackets 31,

which are used to secure the base 18 to the running board 14, I pivot toggle arms 33 upon pins 34. The arms 21 are pivotally secured to the toggle arms 33 upon riveted pins 35. To the lower end of the toggle arms 33, I swingably attach by means of pins 36 a member 40 which extends around the front 41 of the base 18 when the parts are disposed in locking arrangement and has a clip 42 mounted centrally thereupon, the member 40 and the clip 42 being received by a clip 43 mounted upon the front 41 of the base.

I provide a shallow groove 45 in that portion 46 of the member 40 extending across the front 41 of the base in order to stiffen the member 40. It will be perceived that the clips 42 and 43 are formed to concur with the groove 45 and that when the arm 40 is lowered into the clip 43, the front extending portion 46 of the member must be sprung inwardly in order to pass and fit over the indented portion 48 of the clip 43. Upon the outer face of the base 18 are formed bumped portions 49 against which the member 40 rests when in the position shown in the drawings and in combination with the spring action of the member 40 prevents any vibration of the member 40. Holes 50 extending through both the clips 42 and 43 are concurrent when the clips are engaged, through which holes the shackle 51 of a padlock 52 may be passed to securely lock the mounting so that the containers cannot be removed therefrom.

Clips 55, having inwardly bent toes 56, are also pivoted upon the pins 36, the toes 56 serving to prevent the member 40 assuming a position relative to the toggle arm 33 at an angle of less than 90 degrees, as shown in Fig. 2. When it is desired to remove any of the containers, the lock 52 is removed and the front portion 46 of the member is lifted, causing the toggle arm to swing forwardly around the pivot 34 as the portion 46 of the member 40 moves upwardly. When the clip 42 has been lifted out of the clip 43, the member 40 may be pulled outwardly to swing the toggle arm 33 into the position shown in dotted lines 60 in Fig. 2. This action raises the arm 21 sufficiently to allow the cover 19 to swing outwardly freely over the tops of the containers into a position to the front of the containers, as indicated by the dotted lines 61 of Fig. 2, whereupon the

containers may be conveniently removed from the base 18. Through the lower leg 65 of the bracket 31, I extend machine screws 66 which pass through the running board 14 and have mounted upon the lower ends thereof nuts 67 contained in cup members 68 which are provided with prongs 69 that may be embedded in the under side of the running board 14 by tightening the screws 66 through the nuts 67. When the prongs 69 are securely embedded in the under side of the running board, it is impossible to turn the nut 67 upon screw 66 as the formation of the cup 68 prevents the use of a wrench thereupon, and it is therefore necessary to remove the screws by turning them from above with a screwdriver. When the containers are locked in the mounting, the heads of the screws 66 are covered thereby, and access to the heads of the screws 66 is prevented making it impossible to remove the emergency unit from the car under such conditions.

I claim as my invention:

- 25 1. In a mounting for containers, the combination of: a base to receive the lower portions of said containers; a cover member adapted to enclose the upper portions of said containers; toggle arms pivoted upon said base; arms connecting said cover and swingably joined with said toggle arms at points other than said pivots; and connected arms swingably attached to said toggle arms for rotating said toggle arms upon said pivots.
- 30 2. In a mounting for containers, the combination of: a base to receive the lower portions of said containers; a cover member adapted to enclose the upper portions of said containers; toggle arms pivoted upon said base; arms connecting with said cover and swingably joined with said toggle arms at points other than said pivots; connected arms swingably attached to said toggle arms for rotating said toggle arms upon said pivots; and means for locking said arms in confined position.
- 35 3. In a mounting for containers, the combination of: a base to receive the lower portions of said containers; a cover member adapted to enclose the upper portions of said containers; toggle arms pivoted upon said base; arms connecting with said cover and swingably joined with said toggle arms at points other than said pivots; connected arms swingably attached to said toggle arms for rotating said toggle arms upon said pivots; and means for locking said arms in confined position.
- 40 4. In a mounting for containers, the combination of: a base to receive the lower portions of said containers; a cover member adapted to enclose the upper portions of said containers; toggle arms pivoted upon said base; arms connecting with said cover and swingably joined with said toggle arms at points other than said pivots; connected arms swingably attached to said toggle arms for rotating said toggle arms upon said pivots; and means for locking said arms in confined position.
- 45 5. In a mounting for containers, the combination of: a base to receive the lower portions of said containers; a cover member adapted to enclose the upper portions of said containers; toggle arms pivoted upon said base; arms connecting with said cover and swingably joined with said toggle arms at points other than said pivots; connected arms swingably attached to said toggle arms for rotating said toggle arms upon said pivots; and means for locking said arms in confined position.
- 50 6. In a mounting for containers, the combination of: a base to receive the lower portions of said containers; a cover member adapted to enclose the upper portions of said containers; toggle arms pivoted upon said base; arms connecting with said cover and swingably joined with said toggle arms at points other than said pivots; a connecting member extending between said toggle arms; a clip formed upon said connecting member; and a clip mounted upon said base to springably receive said member clip; said clips having coinciding holes therethrough to receive a locking means.

said base; arms connecting with said cover and swingably joined with said toggle arms at points other than said pivots; a substantially U-shaped member having the ends thereof swingably attached to the free ends of said toggle links; and means for locking said member against said base; substantially as described.

4. In a mounting for containers, the combination of: a base to receive the lower portions of said containers; a cover member adapted to enclose the upper portions of said containers; toggle arms pivoted upon said base; arms connecting with said cover and swingably joined with said toggle arms at points other than said pivots; a substantially U-shaped member having the ends thereof swingably attached to the free ends of said toggle links; and means for locking said member against said base; substantially as described.

5. In a mounting for containers, the combination of: a base to receive the lower portions of said containers; a cover member adapted to enclose the upper portions of said containers; toggle arms pivoted upon said base; arms connecting with said cover and swingably joined with said toggle arms at points other than said pivots; a connecting member extending between said toggle arms; a clip formed upon said connecting member; and a clip mounted upon said base to springably receive said member clip; said clips having coinciding holes therethrough to receive a locking means.

6. In a mounting for containers, the combination of: a base to receive the lower portions of said containers; a cover member adapted to enclose the upper portions of said containers; toggle arms pivoted upon said base; arms connecting with said cover and swingably joined with said toggle arms at points other than said pivots; a connecting member extending between said toggle arms; a clip formed upon said connecting member; and a clip mounted upon said base to springably receive said member clip; said clips having coinciding holes therethrough to receive a locking means.

In testimony whereof, I have hereunto set my hand at Los Angeles, California, this 28th day of December, 1921.

OZRO N. WISWELL.
